TOY ROCKET DISPLAY PACKAGE

John B. Ames, Selma, Ala.

Application October 24, 1958, Serial No. 53,142

Term of patent 14 years

(Cl. D80—5)

Fig. 1 is a front elevation view of a toy rocket display package showing my new design; and,

Fig. 2 is a top plan view thereof.

I claim:

The ornamental design for a toy rocket display package, as shown.
